UNITED STATES PATENT OFFICE.

FREDERICK A. SCRANTON, OF EAST HAMPTON, CONNECTICUT.

DESIGN FOR A BELL.

SPECIFICATION forming part of Design No. 33,142, dated August 28, 1900.

Application filed July 27, 1900. Serial No. 25,058. Term of patent 14 years.

To all whom it may concern:

Be it known that I, FREDERICK A. SCRANTON, a citizen of the United States, and a resident of East Hampton, in the county of Middlesex and State of Connecticut, have invented and produced a new and original Design for a Bell, of which the following is a specification, reference being had to the accompanying drawings, forming part hereof.

Figure 1 is a view in side elevation of a bell, showing my design. Fig. 2 is a plan view of the same.

As shown in the drawings, the leading or material feature of my design consists of a body part *a* in the form of an oblate spheroid and having at one end a circular base *b*, joined with the body portion *a* by a smaller neck portion *c*, which flares out from the

point of union with the body part to its point of connection with the base *b*. The body portion of the bell in the form of an oblate spheroid has its end approaching a form nearly flat, as shown in the drawings.

Having described my invention, what I claim as new, and desire to secure by Letters Patent, is—

The design for a bell as herein shown and described.

In testimony whereof I have set my hand to this specification in the presence of two subscribing witnesses.

FREDERICK A. SCRANTON.

Witnesses:

MAY L. PURPLE,
LENA I. EMERSON.
